(57) **CLAIM**

We claim the ornamental design for a charger, as shown and described.

DESCRIPTION

FIG. 1 is a perspective top view of a new design for a charger;

FIG. 2 is a perspective bottom view thereof;

FIG. 3 is a front view thereof;

FIG. 4 is a rear view thereof;

FIG. 5 is a left side view thereof, the right side view being a mirror image thereto;

FIG. 6 is a top view thereof; and,

FIG. 7 is a bottom view thereof.

The broken lines in the figures represent portions of the article which form no part of the claim. The broken away symbols in the drawings indicate that any portion of the article beyond what is shown forms no part of the claimed design.

1 Claim, 6 Drawing Sheets
